BRUSH TRIMMING AND BENDING MACHINE

Theodore Marks, John Jimenez, and Luis M. Jimenez, Bronx, N. Y., assignors to American Brush Machinery Co., Inc.

Application November 15, 1949, Serial No. 127,462

8 Claims. (Cl. 300—17)

1

This invention relates to a brush trimming and bending machine for twisted wire brushes.

Twisted wire brushes are generally formed by inserting a group of bristles from which it is intended to form a brush between a pair of wires which are then twisted together thereby firmly securing the bristles between said wires. During the twisting process, which is generally carried on in a twisting lathe, many of the bristles are displaced making it necessary to trim said brushes to a uniform diameter. It has also been found desirable to form these type of brushes to present a tapered or similar peripheral surface. Such or similar configurations may be imparted to the peripheral surface of the brush by the use of appropriately shaped or positioned trimming knives to trim the brush after it has been formed in the manner indicated. Additionally it is the practice to form said brushes into a variety of shapes such as ovals or circles in order to adapt them to a variety of uses. In so forming or bending the brushes the ends thereof are brought into adjacency with one another thereby permitting said brushes to be ultimately mounted in a handle by inserting the ends of the brush into an axial bore provided therein.

It is the object of this invention to provide a machine into which bristles may be successively fed for the purpose of trimming the peripheral surface of said brush to a desired configuration and then bending said brush to a desired shape. It is a further object of this invention to provide a mechanism which will automatically and successively present brushes to a trimming device for the purpose of trimming the peripheral surface thereof and thereafter to automatically present said brushes to the operation of bending and forming means provided in said device, and to provide additional means for ejecting a brush so formed from the machine.

Other and further objects of this invention will become apparent from the description thereof contained in the annexed specification, or will otherwise be obvious. It will be understood that the invention herein disclosed may be employed for other purposes to which the structure and arrangement are adapted.

In the accompanying drawings:

Figure 1 is a side elevation of the machine;

Figure 2 is a horizontal section of the machine partly broken away taken along line 2—2 of Figure 1;

Figure 3 is a cross-section taken along line 3—3 of Figure 2;

Figure 4 is a front elevation of the upper portion of the machine showing the indexing and knockout and ejection mechanism;

2

Figure 5 is a fragmentary top view of the bending arms and jaws of the machine closed upon the ends of a wire brush taken along line 5—5 of Figure 4;

5 Figure 6 is a fragmentary side view of the knockout and ejection mechanism;

Figure 7 is a fragmentary perspective view of the cam shaft and valve arrangement; and

10 Figure 8 is a view, partly diagrammatic, of the cam shaft and valve arrangement showing the compressed air circuit.

The general type of brush upon which this invention is intended to operate is illustrated in Figure 2 of the drawings. The brush 11 is generally formed by twisting a pair of wires between which bristles, hairs, wires, filaments or fibers of various materials have been inserted, thereby forming a brush having a centrally located bristle portion 12 intermediate the two end portions 13 of bare wire. The general purpose of the device is to provide an appropriate feed mechanism wherein a series of brushes are fed consecutively to a trimming device whereby each of said brushes is reduced to a predetermined or uniform diameter; and thereafter to form or bend said brushes into a desired shape such as the loop illustrated in Figure 5. The bending or forming operation serves to form the brush into a loop and to bring the ends of said brush into close proximity with one another and to so form said ends as to facilitate their insertion into a brush handle or similar holding device.

35 In its broad outline the present invention comprises an arrangement whereby brushes are continuously fed to an indexing dial mechanism. As a result of the operation of said indexing dial mechanism each brush is presented in sequence to a trimming mechanism wherein said brush is reduced to a predetermined or uniform diameter. After the completion of the trimming operation each brush is removed from the indexing mechanism and simultaneously positioned so as to permit a bending mechanism to act upon it for the purpose of imparting the desired shape to each of said brushes. Upon the completion of the bending operation each brush is automatically ejected from the entire machine. It should be noted that in view of the arrangement herein-after disclosed, a brush is in the process being trimmed during the period that a preceding brush is being operated upon by the bending mechanism and a new brush is being presented to the bending mechanism simultaneously with the ejection of a preceding bent brush from the machine.

40 As shown in Figure 1, the entire device is sup-

ported upon supporting table 14. Disposed upon a shelf 15 formed in the lower portion of said supporting table is main motor drive 16 which actuates cam shaft 17 through reduction gear assembly 18 and determines the timing relation of the various elements of the device. Located in the upper portion of said supporting table is main plate 19 whereon is located trimmer assembly 20 and its associated motor drive 21 as well as the indexing and bending mechanism which will hereinafter be more fully described. The entire device is timed so that when fed continuously a completely trimmed and bent brush is ejected therefrom upon each complete revolution of cam shaft 17.

Indexing dial mechanism

As shown in Figures 1 and 4, the indexing dial mechanism comprises a pair of indexing dial discs 22, 23, along the periphery of which notches 24 are formed at equally spaced intervals. The notches on each of the discs located are at similarly spaced intervals so as to permit their alignment in order to support the ends of a brush therein. Dial discs 22, 23 are keyed to rotate with shaft 25 and are journaled in standards 26, 27 which are secured at the sides of supporting table 14. Dials 22, 23 are securely located on shaft 25 by means of set screws 28, 29 which thus permit such location along the shaft to be varied in order to accommodate brushes of varying lengths. Figure 4 shows a brush 11 in position in a pair of dial discs notches 24.

As shown in Figures 1 and 4, substantially half of the circumference of discs 22, 23 is surrounded by guard plates 30 and 31 respectively. Guard plates 30 and 31 are positioned in spaced relation to the peripheral surfaces of discs 22 and 23 respectively but are sufficiently close so as to prevent the displacement of brush ends 13 from notches 24 while a brush 11 is being supported by said discs and being operated upon by the elements of the machine. In order to permit the alignment of guard plates 30 and 31 with discs 22, 23, as said discs are variously positioned along shaft 25 for the accommodation of brushes of varying lengths; each of said guard plates is provided with a screw threaded portion 32 which is adapted to receive a portion of screw bars 33, 34. Said screw bars are journaled in standards 26, 27, one end 35 of the upper screw bar 33 being adapted to engage with a detachable hand crank or similar device, not shown. Each half of each of the screw bars is threaded in reverse direction from the center. Sprocket wheels 36, 37 are keyed to bars 33, 34 respectively and a driving connection is provided between said wheels by means of sprocket chain 38. It will thus be seen that upon the rotation of upper screw bar 33 by means of a hand crank as indicated above, both of said bars will be caused to rotate simultaneously and cause guard plates 30, 31 to be simultaneously moved to a position symmetrically from the centers of said bars and to any desired distance from each other in order to accommodate brushes of varying lengths. By means of this arrangement the position of the guard plates may advantageously be utilized as guides to indicate the proper location of the discs 22, 23 for a particular length brush thereby permitting the positioning of said brush substantially centrally of the machine.

Indexing movement is imparted to discs 22, 23 by means of a ratchet drive arrangement. One end of shaft 25 is extended beyond its support-

ing standard 26 and ratchet wheel 39 is keyed thereto. Ratchet wheel 39 engages with pawl 40 which is carried by crank arm 41. One end of said crank arm is rotatably mounted on the end of shaft 25, said crank being actuated by rod 42 which is linked to crank disc 43 mounted on shaft by means of a pin. It will therefore be seen that the rotation of crank disc 43 will cause discs 22, 23, to advance intermittently in the direction indicated by the arrow adjacent to said discs in Figure 1. The arrangement is such as to cause said discs to be rotated through the arc between adjacent notches 24 thus causing said discs to index one position stepwise upon each rotation of cam shaft 17. Brushes may be fed or positioned in the notches in the discs in succession, manually, or by means of a hopper or similar arrangement and each brush is advanced stepwise in order to permit the elements of the machine to operate upon each of them successively. The first such operation is the trimming operation which reduces said brush to cylinder of the desired or uniform diameter.

Trimmer assembly

As a brush is advanced by the indexing mechanism it is positioned directly opposite trimmer assembly 20 as indicated by the letter A in Figure 1. Said assembly comprises a housing 44 within which drum 45 is rotated with shaft 46. Said drum is rotated by means of motor 21 through drive belt 47 and a pulley located at one end of said drum. Radially extending trimmer blades 48 are positioned in the periphery of said drum and are adapted to cooperate with stationary trimmer blade 49 secured to said housing by means of adjustable screw bolt assembly 50 thus permitting the adjustment of the position of stationary blade 49 with reference to blades 48 upon the rotating drum for the purpose of bringing them in proximity in order to provide a trimming action. As shown in Figure 2, main plate 19 is provided with slide rails 51 adapted to cooperate with complementary slide rail on the base of trimmer assembly 20 in order to permit the position of said trimmer assembly to be varied with reference to dial discs 22, 23 thereby permitting said machine to be adjusted to trim brushes of various diameters as desired. The trimmer assembly is secured in selected position by means of bolts 52. Since discs 22, 23 index one position for each rotation of cam shaft 17 it will be seen that a fresh brush is presented to the operation of the trimmer assembly upon each such rotation. The brushes are freely rotatable in notches 24 and the rotation of drum causes blades 48 to strike the bristles of said brush and imparts rotary movement to the brush as it is being trimmed, thereby causing the entire circumferential surface of the brush to be trimmed as desired.

Upon the completion of the trimming operation the brush is advanced two positions stepwise and arrives at the position indicated by the letter B in Figure 1, at which point it is properly positioned for removal from the discs by the knockout assembly in order to be operated upon by the bending and forming mechanism.

Knockout and ejector assembly

As shown in Figure 4, the knockout and ejector assembly is mounted on bridge plate 53 which is secured to main plate 19 by means of posts 54. Secured to bridge plate 53 are brackets 55, 56 which rotatably carry shaft 57. Secured to said

shaft for rotation therewith are arms 58 to which knockout plates are secured as is more clearly shown in Figures 1, 4, and 6. Connecting arms 58 is cross bar 69 which carries ejector 61. It will thus be seen that upon rotation of shaft 57 through a portion of a revolution, knockout plates 59 and ejector 61 are lowered simultaneously. Rotary movement is imparted to said shaft by means of a rack and pinion assembly.

Keyed to one end of shaft 57 is pinion 62 which 10 engages with rack 63. Said rack is slideably mounted on plate 64 which is secured to bridge plate 63. Said rack is secured to piston rod 65 of air cylinder 66 which it reciprocably actuates said rack thereby rotating shaft 57 by means of pinion 62 through a portion of a revolution and simultaneously depressing knockout plates 59 and ejector 61. The knockout plates and ejector are raised by the reverse movement of the rack.

Guard plates 30, 31 do not extend below the position of the notch in dial discs 22, 23 indicated by the letter B in Figure 1. Thus as each pair of notches reaches said position the brush which is located therein is free to drop therefrom. In order to retain temporarily said brush within said notches, a latch assembly is provided immediately below said position. The latch assembly comprises a latch arm 67, counterweight 68 carried by said latch arm and a pivot post 69 intermediate said elements. Counterweight 68 retains latch arm 67 in raised position thereby acting as a closure for the notches positioned at B and temporarily retaining the brush positioned within the notches. The removal of the brush from the dial discs at this point is accomplished by means of the action of knockout plates 59. As said plates are lowered by action of rack 63 reciprocated by means of air cylinder 66; the brush acts to force latch arm 67 downwardly until the brush passes the end of said arm which is then returned to its normal up position by means of counterweight 68. The brush is brought to rest upon bender posts 70 as more clearly appears from Figures 2 and 6 thereby appropriately positioning said brush for the bending operation.

Mandrel and wedge assembly

The brush is formed or bent around a mandrel and wedge assembly comprised of mandrel 71 and wedge 72. The mandrel is more clearly illustrated in Figures 3 and 5 and is shown as cylindrical, said form being advantageous in order to form a brush of the common looped variety. It will be understood however that the configuration of said mandrel may be varied or a number of them may be utilized in order to produce bends of different configurations. The mandrel is secured to one end of the slide 73. Slide 73 is provided with a longitudinal slot 75 whereby it may be adjustably secured to bridge plate 53 by means of bolt 74 in order to permit the adjustment of said slide for brushes or mandrels of varying diameters. A brush formed around the mandrel is shown in Figure 5. As appears from said figure, the ends 13 of the brush are bent at 76 in order to facilitate the insertion of said brush within a cavity in a handle. This bend is accomplished by the interposition of wedge 72 between the ends 13 of said brush while it is being bent around the mandrel. Dependently secured to slide 73 is post 77 to which wedge 72 is adjustably secured by means of bolt 78 passed through slot 79 in said wedge. Thus the location of the bend in the wire ends may be varied as well as the angle thereof by the adjust-

ment of the position of the wedge or by substitution of wedges of different thickness.

Bending mechanism

As the brush is brought to rest upon bender posts 70 it is brought to bear and is firmly positioned against mandrel 71 by means of fork 80. As more clearly appears from Figures 2 and 3, said fork is secured to rod 81 which is slideably mounted for reciprocation in guides 82. The remote end of rod 81 is secured to the piston rod of air cylinder 83 which in turn is secured to main plate 19. A collar 84 is adjustably positioned on rod 81 and acts as a stop to limit the forward movement of said rod and the fork element secured thereto. Upon the forward actuation of rod 81 by means of air cylinder 83, the fork engages a portion of the brush wires and causes said brush to bear firmly against mandrel 71. It will be noted that the brush ends slide along and continue to rest upon posts 70. As a result of this arrangement displacement of the brush from its proper position during the bending operation is prevented.

As shown in Figure 1, the bending mechanism is actuated by means of air cylinder 85 located upon the shelf 15 carries by supporting table 14. Said air cylinder is mounted vertically and pivotally secured to said shelf at 86. Piston rod 87 of said air cylinder has pivotally secured thereto toggle arms 88, 89. Arm 88 is pivotally secured to plate 90 which is adjustably positioned upon the main plate by means of bracket and screw arrangement 91. Arm 89 of said toggle is pivotally secured to rack 92 which is slideably mounted for reciprocable movement in slide 93 secured to the undersurface of plate 19. It will thus be seen that when the piston rod 89 of air cylinder 85 is moved upwardly toggle arms 88, 89 spread, and assume a more nearly horizontal position, moving rack 92 forward. A small degree of adjustment is provided for the extent movement of said rack by reason of the adjustment which may be made in the position of plate 90 upon which arm 88 of said toggle arrangement is anchored.

As more clearly appears from Figure 4 rack 92 meshes with gear 94 which is in mesh with gear 95 of similar diameter. Said gears are supported by housing 96 depending from the undersurface of plate 19. Gears 94, 95 are keyed to shafts 97, 98 respectively. As shown in Figures 3 and 4, the lower ends of said shafts are carried by bearings 99 and 100 respectively. The upper ends of said shafts are carried by bearings 101, 102 supported by main plate 19. As a result of the meshing of gears 94 and 95 in this arrangement shafts 97 and 98 are caused to be counter-rotated upon the movement of rack 92.

The bending arm assembly is supported by means of front crank plate 103 and rear crank plate 104 each of which is secured to main plate 19 as is more clearly shown in Figure 2. Bending arms 105, 106 are linked to the rear crank plate by means of rear crank arms 107 and 108 respectively. Forward crank arms 109, 110 are keyed to the ends of shafts 97 and 98 respectively which extend above the surface of crank plate 103. The free ends of said crank arms are provided with a series of perforations 113 which are adapted to receive bolts in order to pivotally secure each of the bending arms to the forward crank arms. By selecting the appropriate perforations the initial and clamping position of the bending arms may be adjusted for the accom-

modation of various sizes of brushes and bends. Secured to the ends of each of bending arms 105 and 106 and disposed at an angle with relation thereto are bending jaws 111 and 112 from each of which a bender post 70 extends. It will thus be seen that the forward movement of rack 92 results in the rotation of gears 94 and 95 toward each other as viewed from the front of the machine and as a result thereof bending jaws 111 and 112 are caused to move in a forward direction toward each other as viewed from the front of the machine thus bending the brush around the mandrel and wedge. The resultant position of the elements of the bending crank assembly are indicated by the broken lines in Figure 2; the position of the bending jaws and brush being shown in Figure 5. Upon the rearward movement of the rack the gears rotate away from each other thereby restoring the bending assembly to its previous position. The simultaneous forward and inward movement of the bending jaws results in a more uniform and smooth bend in the brush around the mandrel. It has been found advantageous to form said bending jaws with beveled edges 114 and 115 in order to provide a suitable contact surface between the bending jaws and the brush ends during the bending movement.

It will be noted that during the completion of the bend, the ends of the brush are automatically bent at 76 as shown in Figure 5, by reason of the interposition of wedge 72 between said brush ends. It will also be noted that the entire bending arrangement is disposed in a plane parallel to the main plate 19 and that the bending of the brush is carried on the same plane. The brush is firmly positioned on posts 70 at all times during said operation until the final phase of the bend is accomplished.

Timing mechanism

The timing of the various operations carried on by the machine is determined by the rotation of cam shaft 17 as more particularly shown in Figures 7 and 8. Shaft 17 is keyed to cams 116, 117 and 118. Associated with said cams are followers 119, 120 and 121, which in turn actuate air valves 122, 123 and 124 respectively. Said air valves are connected to a common source of compressed air. Suitable tubing or similar conduits are provided to carry the compressed air from said valves to the various air cylinders which operate the mechanisms of the machine. The knockout and ejector assembly are operated by air cylinder 66 which is supplied with compressed air at suitable intervals through valve 122 which is actuated by cam 116 on cam shaft 17. In the position of shaft 17 indicated in Figure 1, the crank pin has reached its highest position thereby causing pawl 40 to reach the limit of its movement and terminating the indexing movement of dials 22, 23. A brush is then located at the station indicated by the letter A and the trimmer blade which is constantly rotating causes said brush to be trimmed during such stationary or dwell period. A brush is similarly at the position indicated by the letter B and rests upon latch arm 67. As shaft 17 continues to rotate and reaches a position approximately 10° in the direction indicated, cam 116 begins to open valve 122 which actuates air cylinder 66 and causes the knockout plates to descend upon said brush and firmly position it on posts 70 thereby properly positioning it for the operation of the bender mechanism. As heretofore indicated, ejector 61 descends simultaneously and ejects the previously

bent brush through an opening 125 in main plate 19. The knockout and ejector action is more clearly illustrated in Figure 6.

As said brush comes to rest upon posts 70 and 5 after the shaft has rotated approximately an additional 10° from the point previously indicated, the action of cam 17 begins to open valve 123 thereby introducing compressed air into the cylinder 83 which begins to move fork 80 forward, as said fork reaches its foremost position 10 it moves the brush along posts 70 and firmly positions the brush against mandrel 71. When the brush has been firmly positioned against the mandrel by fork 80 which occurs after an additional 15° rotation of shaft 17 from the point heretofore indicated, cam 116 again actuates valve 122 and causes air cylinder 66 to return to its previous position. Arms 58 are thereby caused to return to their raised position.

Upon the additional rotation of cam shaft 17 through approximately 5° valve 124 is actuated by cam 118 and causes piston rod 81 of air cylinder 85 to be raised, thereby spreading arms 88, 89 and causing the bending arms 105, 106 to be 20 actuated to bend said brush around mandrel 71. Fork 80 and the bending arms 105, 106 remain in actuated forward position as cam shaft 17 continues to rotate additionally for approximately 30 145° at which time crank disc 42 has reached its lowermost point and begins to rise thereby initiating the rotation of the dial discs for the next position. Upon an additional rotation of said cam shaft through 20° fork 80 is 35 returned to its normal rearward position by means of the actuation of air cylinder 83 resulting from the operation of cam 117 on valve 123. Air cylinder 85 is then returned to its previous position after an additional rotation of cam shaft 17 through approximately an additional 15° by 40 means of the action of cam 118 on valve 124 and retracts bending arms 105, 106 thereby opening the bending jaws. As cam shaft 17 reaches its original position indicated in Figure 1, the dial discs have arrived at their next position and the 45 operating cycle of the machine is repeated.

We have here shown and described a preferred embodiment of our invention. It will be apparent, however, that this invention is not limited to this embodiment and that many changes, additions and modifications can be made in connection therewith without departing from the spirit and scope of the invention as herein disclosed and hereinafter claimed.

Having described our invention, what we 55 claim as new and desire to secure by Letters Patent is:

1. In a twisted wire brush trimming and bending machine, a support, a shaft rotatably carried by said support, dial discs mounted on said shaft, circumferentially spaced slots formed in the periphery of said discs adapted to support the ends of a twisted wire brush when positioned therein, guard plates extending around substantially half of the peripheral surface of each of said discs terminating short of the lowermost station of said discs and adapted to prevent the displacement of such brush from said slots, a latch positioned below said lowermost station of said discs and adapted to removably retain such brush within said slots.

2. In a twisted wire brush trimming and bending machine, a support, a shaft rotatably carried by said support, dial discs mounted on said shaft for rotation therewith, circumferentially spaced slots formed in the periphery of said discs

adapted to support the ends of a twisted wire brush when positioned therein, a rotary trimming drum in spaced relation to said discs adapted to trim the peripheral surface of such brush as it is stationed in juxtaposition thereto by said discs, a rotatably mounted shaft axially parallel with the axis of said discs, a pinion secured to said shaft for rotation therewith, a rack in engagement with said pinion, an air cylinder adapted to reciprocate said rack, arms extending from said shaft, depending plates carried by said arms adapted to descend upon such brush positioned in the slots in said discs and thereby remove said brush from said discs, a depending post carried by said arms and adapted to simultaneously eject a brush from said machine.

3. In a brush trimming and bending machine, a support, a shaft rotatably carried by said support, discs mounted on said shaft, each of said discs being provided with circumferentially spaced slots adapted to receive the ends of a twisted wire brush, set screws mounted on the hubs of said discs for selectively positioning said discs along said shaft, a guard plate extending around substantially half of the circumference of each of said discs and adapted to overlie said slots in order to retain the brush ends therein, screw threaded perforations in the upper and lower portions of said guard plates, rotatable screw threaded bars adapted to be 30 threadedly received in said perforations and to position said guard plates, each half of each of said bars being threaded in a reverse direction, a sprocket wheel positioned on each of said bars for rotation therewith, and a sprocket chain interconnecting said wheels for simultaneous rotation.

4. A brush trimming and bending machine comprising a support, a main plate carried by said support, a shaft rotatably carried by said support, indexing dial discs mounted on said shaft and provided with circumferentially spaced slots adapted to support the ends of a brush, means to intermittently rotate said indexing dials to advance one station at a time, a rotary trimming drum carried by said support and positioned in spaced relation to said dials and adapted to trim the peripheral surface of each brush as it is presented thereto by said indexing dials, guard plates adapted to surround a portion of said indexing dials and adapted to retain a brush within said slots, a pair of pivotally mounted plates adapted to remove a trimmed brush from said indexing dials, a mandrel around which a brush may be bent, a wedge shaped element positioned in spaced relation to said mandrel, a reciprocable fork adapted to retain a trimmed brush against said mandrel, a pair of bending arms adapted to bend said brush around said mandrel and wedge, a pivotally mounted depending post adapted to eject a bent brush from said machine.

5. The device according to claim 4 wherein said pivotally mounted plates and said depending post are secured to a common shaft being adapted to remove a brush from said indexing dials simultaneously with the ejection of a brush from the machine.

6. The device according to claim 4 wherein the means to intermittently rotate said indexing dials are comprised of said shaft to which said indexing dials are secured, a pair of standards adapted to rotatably support said shaft, a ratchet wheel secured to one end of said shaft, a pawl

adapted to engage with said ratchet wheel, a crank arm rotatably mounted on said shaft, a motor drive, a cam shaft adapted to be rotated by said motor drive, a crank disc secured to said cam shaft and a rod linking said crank disc to said crank arm whereby said indexing dials are advanced one station upon each rotation of said cam shaft.

7. The device according to claim 4 wherein bending jaws are secured to one end of each of said bending arms and a crank arm is pivotally secured to the rear portion of each of said bending arms, the other ends of said crank arms being pivotally secured on said main plate, a crank arm pivotally secured to the forward portion of each of said bending arms, a pair of meshed gears rotatably carried by said plate, shafts secured to said gears, one end of each of said shafts being secured to the free ends of said latter crank arms whereby said bending arms are moved forwardly and toward each other upon the rotation of said gears in one direction and away from each other when the direction of rotation of said gears is reversed, a reciprocable rack in mesh with one of said gears adapted to rotate said gears upon the reciprocation thereof.

8. A brush trimming and bending machine comprising a support, a shaft rotatably carried by said support, indexing dials carried by said shaft and provided with circumferentially spaced slots adapted to support the ends of a wire brush, means to intermittently rotate said indexing dials to advance one station at a time, a rotary trimming drum carried by said support and positioned in spaced relation to said dials and adapted to trim the peripheral surface of each brush as it is presented thereto by said indexing dials, guard plates adapted to surround a portion of said indexing dials within said slots, a pair of pivotally mounted plates adapted to remove a trimmed brush from said indexing dials, a mandrel around which a brush may be bent, a wedge shaped element positioned in spaced relation to said mandrel, a reciprocable fork adapted to retain a trimmed brush against said mandrel, a pair of bending arms adapted to bend said brush around said mandrel and wedge, a pivotally mounted depending post adapted to eject a bent brush from said machine, a motor drive, a rotatable cam shaft adapted to be rotated by said drive, cam elements mounted on said shaft, cam followers adapted to cooperate with said cams, air valves adapted to be actuated by said followers, an air cylinder adapted to simultaneously actuate said pivotally mounted plates and said depending post and compressed air conduits connecting said air cylinder with one of said air valves, a second air cylinder adapted to reciprocate said fork, compressed air conduits connecting said air cylinder with a second of said air valves, a third air cylinder adapted to actuate said bending arms, compressed air conduits connecting said third air cylinder with a third of said air valves.
